RADIO HOUSING FOR EYE GLASSES

Jack C. Roberts, Malibu, Calif., assignor to Saxton Electronics Corporation, Congers, N.Y., a corporation of New York

Filed Feb. 7, 1968, Ser. No. 10,470

Term of patent 14 years

(Cl. D56—4)

FIGURE 1 is a perspective view of the radio housing for eye glasses showing my new design;

FIGURE 2 is a side elevational view thereof;

FIGURE 3 is a top plan view thereof;

FIGURE 4 is a side elevational view thereof as taken from the opposite side shown in FIGURE 2;

FIGURE 5 is a bottom plan view thereof;

FIGURE 6 is a rear end view thereof; and

FIGURE 7 is a front end view thereof.

The broken line showing of the eye glasses is merely for illustrative purposes.

I claim:

The ornamental design for a radio housing for eye glasses, substantially as shown and described.
